UNITED STATES PATENT OFFICE

ERNEST HAMWI, OF ST. LOUIS, MISSOURI

DESIGN FOR A PASTRY CUP

Application filed January 9, 1930. Serial No. 34,064. Term of patent 14 years.

To all whom it may concern:

Be it known that I, ERNEST HAMWI, a citizen of the United States, residing at the city of St. Louis and State of Missouri, have invented a new, original, and ornamental Design for Pastry Cup, substantially as shown in the accompanying drawing, in which—

Fig. 1 is a perspective view of a pastry cup showing my new design.

Fig. 2 is a vertical transverse sectional view of the cup.

I claim:

The ornamental design for a pastry cup, substantially as shown.

ERNEST HAMWI.
